OR D 282

Letter Patent No 282. Dated May 14. 1850.

*In the name of John Johnson
John Hart, design for twisted flannel. Dated May 14. 1850.*

File. 182

Deborah Powers Albert E. Powers & Nathaniel B.
Powers Assignees of James Hutchinson of Troy, N. Y.
Letters Patent No 282. Dated May 14. 1850.

The Schedule referred to in these Letters Patent and making part of the same.

To all whom it may concern:

Be it known, that I, James Hutchinson
of Troy in the County of Rensselaer and State of New York, have invented and pro-
duced, a new design or figure to be printed or stamped upon floor oil cloths, and I
do hereby declare that the following is a full and exact description of the
same. viz

The pattern is divided into compartments of various
regular forms, by bands of different shades of color, so arranged that the compartments have the
appearance of being sunk below the surface of the bands.

The compartments, or grounds between the bands, being
of various shades of color, and each of them ornamented in or near its centre by a repre-
sentation of an object with the coloring so arranged as to give the object the appearance
of being raised above the surface of the several compartments or grounds upon which they are
placed; the general arrangement and details of the pattern, being shewn up on the annexed copy or
drawing, which forms part of this specification.

And what is claimed as my invention and desired
to be secured by Letters Patent of the United States is the arrangement of ornamental figures
forming a design for floor cloths as shewn in the aforesaid drawing.
